DESIGN FOR LACE

Daniel F. Siegrist, Glen Rock, N. J., assignor to American Fabrics Company, Bridgeport, Conn.

Application October 17, 1936, Serial No. 65,340

Term of patent 3½ years

To all whom it may concern:

Be it known that I, Daniel F. Siegrist, a citizen of the United States, residing at No. 51 Bedford Place, in the county of Bergen, city of Glen Rock, State of New Jersey, have invented a new, original, and ornamental Design for Lace, of which the following is a specification, reference being had to the accompanying drawing, forming part hereof.

The drawing shows a face view of a piece of lace embodying my design.

I claim:

The ornamental design for lace, substantially as shown.

D. F. SIEGRIST.
